(57) **CLAIM**

We claim the ornamental design for a pipe coupling segment, as shown and described.

DESCRIPTION

FIG. 1 is an isometric view of our design for a pipe coupling segment;

FIG. 2 is a front view of the design for the pipe coupling segment shown in FIG. 1, the rear view being identical;

FIG. 3 is a top view of the design for the pipe coupling segment shown in FIG. 1;

FIG. 4 is a bottom view of the design for the pipe coupling segment shown in FIG. 1; and,

FIG. 5 is a left side view of the design for the pipe coupling segment shown in FIG. 1, the right side view being identical.

The broken line showing of portions of the pipe coupling in FIGS. 1-5 forms no part of the claimed design.
